UNITED STATES PATENT OFFICE.

JAMES WHITE, OF CANTON, OHIO.

SAFE-LOCK.

SPECIFICATION forming part of Letters Patent No. 292,388, dated February 12, 1884.

Application filed May 23, 1883. (No model.)

To all whom it may concern:

Be it known that I, JAMES WHITE, a citizen of the United States, residing at Canton, in the county of Stark and State of Ohio, have 5 invented certain new and useful Improvements in Locking Mechanism for Safes, of which the following is a specification, reference being had therein to the accompanying drawings.

Figure 1 is an inside elevation of a safe-10 door having my improvements applied thereto, this figure showing also in section the side walls of the safe. Fig. 2 is an inside elevation of a part of the devices shown in Fig. 1 on a larger scale. Fig. 3 is a view, partly in 15 horizontal section, on the axis of the arbor, and showing also some of the devices inside of the safe in top plan. Fig. 4 is a vertical section of the front wall of the safe, showing the arbor in side elevation, showing also a part of 20 the inside of one of the side walls in elevation, and one of the plates of said wall in section. Fig. 5 is a side view of the crank-wheel detached. Fig. 6 is an end view of the same. Fig. 7 is a face view of the cam on the tumbler 25 shaft or spindle. Fig. 8 is a view showing in horizontal section a portion of the draw-bar connected with the bolts, and showing in top plan the plate or bar with which said locking-bar can be detachably connected, and a part 30 of the swinging lever which engages with the arbor. Fig. 9 is a view of the handle-support, partly in section. Fig. 10 is a sectional view of the loose sleeve on the arbor-spindle. Fig. 11 is an inner end view of the same. Fig. 12 35 is an outer end view. Fig. 13 shows detached the spring combined with the handle at the outer end of the arbor.

The main frame-work of the safe—the top, bottom, and sides thereof—may be constructed 40 in any suitable way, though I prefer to make these parts in the manner which I have shown and described in another application.

In the drawings, A represents generally the door, constructed of plates, preferably in the 45 manner which I have shown in the aforesaid application, and upon the inside of this are mounted the locking-bolts. These bolts consist of arms B' B', arranged in pairs at each corner of the door. One of each pair projects laterally and the other vertically across the 50 vertical and horizontal edges of the door. The

arms of each pair are carried by a hub, B², which also carries a lever-arm, B³. The two pairs of arms, near the hinges, are connected by a vertical link or bar, C', and the other 55 two pairs are connected by a bar or link, C², the two links being pivotally connected to the upper and lower lever-arms B³.

D' D' are supplemental bolt-arms situated near the central horizontal line of the door, 60 and adapted to be thrust laterally outward beyond the edges thereof. These are pivoted at d, and have inwardly-projecting lever-arms D², which are pivoted also to the links or bars C' C². All of these locking-bolts are operated 65 simultaneously by means of a lever, E' E² E³, the arm E' being pivoted to the link C', the arm E² being pivoted to the arm C², and the arm E³ being pivoted to the locking draw-bar R. The said draw-bar extends to or nearly to 70 the edge of the door, and there is attached to the devices by which it is operated.

Q is a lever pivoted to the inside of one of the stationary walls, and at a point part way up it is provided with a slotted arm, Q', by 75 which the lever is held in place. At the upper end it is secured by screws to the plate or bar R'. It is provided with a socket or recess at or near the upper end, and in this is pivoted an arm, I, fastened by the pivot q. 80 This arm I carries an inwardly-projecting stud, pin, or bar, S, which is situated above a series of tumblers, J J J, each provided with a notch and pin so related that when they are properly rotated or rocked the notches can be 85 all brought into line beneath the stud or bar S. When the stud or bar S does drop into these notches, a recess or notch, I', in the outer end of the arm is permitted to drop down to engage with a pin, H, which and the operation 90 of which will be hereinafter described.

K is a cam mounted upon the axis of the tumblers J, and having that part of it with the longer radius so arranged as to lift up the pin or bar S to throw the part I away from the 95 pin H.

N is a small roller mounted upon the stud or bar S, and arranged in the vertical plane of the cam K, so that it can roll upon the edge of the cam. The cam K and the tumbler 100 of the series are operated by means of the spur-wheel L, mounted upon the outer end of

the shaft which carries the cam and tumblers, said wheel meshing with another, M, of the same diameter. This latter is carried by the arbor C D E. The arbor is constructed in a superior manner, so as to prevent drilling, and also prevent its being driven inward or being drawn outward. The main and outer portion, C, has a cylindrical part, c, and a conical part, c', the conical part narrowing outwardly, and 5 being fitted into the plates of the wall of the safe in such manner that it is impossible to draw it outward. At c' there is a shoulder between the conical portion and the cylindrical part, which shoulder abuts also against parts of the wall and prevents the arbor from being driven inward. The part c is screw-threaded, and by the thread is attached to the intermediate crank-wheel, D. I have so constructed this crank-wheel that there are no 10 through apertures or holes in it. Therefore there is less danger of its permitting the safe to be tampered with than when constructed as heretofore.

E represents the spindle portion, which is formed or provided with a base-plate, e, that is fastened against the inner face of the crank-wheel D by means of screws. The spindle E projects inward across a recess or open space formed in the inner part of the wall and 15 rests in a seat at W in one of the wall-plates. Between the end of the spindle and the bottom of the seat there is placed a steel disk or button, V, which is supported loosely therein, and which, when there is any pressure exerted 20 on the outer end of the arbor, will revolve with the shaft or spindle, and thus assist in preventing drilling.

F is a sleeve mounted upon the spindle E, and fitted snugly thereto. It carries an ear, 25 F', with a pin, H, which revolves parallel to the spindle E. It is so revolved by means of a crank-pin, G, carried by the wheel D, which latter, when the arbor is revolved, will sooner or later strike against the ear F' and apply 30 power to the pin H. When said pin is in engagement with the bar I, by reason of the latter having been allowed to fall far enough to have the notch I' surround the pin, the power transmitted as above described, by the 35 crank-pin G, to the pin H will result in pushing the arm I and bar R longitudinally. After the engagement with the pin H and arm I has been effected, a movement of the arbor in the direction of arrow 2 will cause the pin G to 40 bear against the side of the ear F', and thus the arbor can be caused to push the arm I in the direction of arrow 1, and thereby draw the bolts across the edge of the door and lock the latter in place. While the arm I is being 45 drawn far enough in the direction of said arrow 1 to lock the door, the cam or eccentric K is being rotated upon its spindle far enough to have its outer portion come below the stud or bar S and throw it out of the notches in the 50 tumblers—that is to say, said stud or pin is thrown upward until it rides above the notches of the tumblers, the arm I being consequently

thrown out of engagement with the pin H. After this has been effected, it will be seen that all connection between the bolts and the arbor 55 has been broken, and it is impossible to restore such connection until a proper combination of the tumblers has been again effected. After the arm I has been thrown up by the cam K, the relative positions of the tumblers may be 60 varied in the usual way by turning the arbor back and forth a sufficient number of times until I accomplish the desired purpose. Upon the outside of the safe there is a numbered dial-plate, which may be of any preferred nature. As the power for sliding the bolts is transferred through the arbor, it is desirable to apply such power advantageously at the outer end of the arbor. This I effect by means of a handle, W³, pivotally connected to the axial 65 part of the arbor.

Y is a disk having a central seat or recess adapted to fit upon the projection c⁴ on the part C of the arbor, and carrying a ball or enlarged projection, Y'. In the latter there is 70 formed a slot to receive the flattened portion of the handle proper, the latter being secured by a screw or bolt, y'. The parts Y Y' are secured to the part C of the arbor by means of the screw c⁵, which is inserted from the bottom of the slot g, and which, therefore, after the parts are joined, is perfectly concealed. The removal of the handle proper and of the parts Y Y' will not assist in gaining access by way of the arbor to the interior of the safe. 75 When the handle is at right angles to the axial part, it can be used as a crank for the application of considerable power to the arbor. When it is desired to rotate or oscillate the arbor rapidly it can be done by swinging the 80 crank upward or outward in a line with the axial part. In order to hold it with a sufficient rigidity thus in line with the inner part, I employ a spring, preferably of the construction shown—that is to say, having the 85 arms y⁶, the central part, y⁷, tending to be thrust outward, and which engages with a socket or recess, y⁸, in the end of the handle. When engaged with said socket or recess, it 90 overcomes the gravity of the handle and holds it in line with the arbor. However the force of the spring is not so great but that by a slight push in the proper direction the handle can 95 be again thrust into an angular position.

The arbor is made of steel and iron of several alternate layers, and so twisted and otherwise treated as to have it fully resist any attack with a drill.

When the bolts are withdrawn, the outward movement of the door is permitted, from the 100 fact that the bar R can move away from the plate or bar R', the apertured part of bar R escaping from the pin r in said plate or bar R'. When the door is again pushed in, the pin r passes into the aperture in the plate R, and the connection is again made between the 105 bolts and the lever Q and arm I.

What I claim is—

1. In a safe, the combination of the bolts

secured to the inner face of the door, the arbor passing through the stationary front wall of the safe at right angles to the door when the latter is closed, the permutation devices supported 5 stationarily upon the front stationary wall of the safe, and arranged substantially as set forth, to be operated by the arbor, means, constructed and operating substantially as described, which connect the bolts with the arbor, and devices, 10 substantially as described, which throw the bolts out of engagement with the arbor.

2. The combination of the arbor provided with the loose collar and projecting pin, and means for preventing the complete rotation of 15 the collar and pin around the arbor, the bolts, the arm I, means which engage said arm with the bolts, and the permutation devices arranged, substantially as set forth, to throw the arm I into and out of engagement with the 20 loose pin on the arbor, substantially as set forth.

3. In a safe, the combination of the bolts secured to the inside of the door, the arbor passing through the front stationary wall of 25 the safe at right angles to the door when the latter is closed, the swinging lever or bar pivoted to the said stationary wall, a catch which automatically connects said lever with the bolts when the door is shut, the permutation 30 devices interposed between the said swinging lever and the arbor, and means, substantially as described, operated by said permutation devices, for intermittently connecting the arbor with the swinging lever, substantially as set 35 forth.

4. The combination of the arbor passing through the front stationary wall of the safe at right angles to the door when the latter is closed, the spur-wheel on the inner end thereof, 40 the tumblers J, the cam K, spur-wheel L, arm I, adapted to be raised and lowered by the cam and tumblers and to be engaged with the arbor, the bolts secured to the inner side of the door, and devices supported upon the 45 stationary wall of the safe, which connect the arbor with the bolt, substantially as set forth.

5. In a safe, the combination of an arbor situated in the front stationary wall, and having its inner end journaled in a fixed bearing 50 independent of the bearing for the outer end, the bolts secured to the inside of the door at one side of the arbor, and the devices which connect the arbor with the bolts, substantially as and for the purposes set forth.

55 6. The combination of the arbor having upon the inner side of the safe an inwardly-projecting spindle, a bearing for the inner end of said spindle having a socket, and a loosely-mounted button situated in said socket at the inner end of said spindle, substantially as and for the purposes set forth.

7. The combination of the arbor carrying the crank-pin G, the sleeve F, carried by and loosely supported on the arbor, the crank-pin 60 H, carried by said sleeve, the permutation devices operated by the arbor, the bolts on the inside of the door, and the means which

intermittently connect the bolts with the arbor, substantially as set forth.

8. In a safe, the combination of the arbor, 70 the permutation devices connected with and operated by the arbor, the bolts, the lever which connects the bolts with the arbor, a laterally-expanded wheel mounted loosely on the axis of the arbor, and a second wheel secured 75 rigidly to the arbor, and provided with a crank-pin adapted to be detachably connected with the aforesaid lever which operates the bolts, substantially as set forth.

9. The combination, with the outer part of 80 the arbor, which tapers outwardly, and is provided with a shoulder adapted to bear against the plates of the wall, of the wheel or intermediate portion secured to the outer part by a screw-thread, and the inwardly-projecting 85 spindle mounted at its inner end in the wall of the safe, substantially as set forth.

10. In a safe, the combination of an arbor having the outer portion, C, formed with a conical part, c', the shouldered part c'', and the 90 threaded portion c, and the wheel D, having the outwardly-projecting conical part and the inner inverted conical part, and united to the part C by a screw-thread, and provided with the eccentric pin G, substantially as and for 95 the purposes set forth.

11. In a safe, the combination of an arbor having the part C, formed with an outwardly-narrowing portion, whereby it is prevented from being drawn outward, and an inwardly-narrowing portion, whereby it is prevented from being driven inward, a bar or arm for connecting the arbor with the bolts, a crank-pin which connects the arbor with said bar, and a wheel or support for said pin, secured 100 to the said part C of the arbor, and of greater diameter, substantially as set forth.

12. In a safe, the combination of the arbor, the permutation devices connected with and operated by the arbor, the bolts adapted to be 110 operated by the arbor, a laterally-swinging lever, and a vertically-swinging arm pivoted to said lever, and adapted, substantially as set forth, to be engaged with and disengaged from the aforesaid swinging lever, as described.

13. The combination of the bolts, the sliding bar carried by the door for operating the bolts, a bar which travels to and fro and is attached to the wall of the safe, a pin adapted to detachably connect the two aforesaid bars together, and means, substantially as described, for connecting the arbor to the bar which is attached to the wall of the safe, and which moves to and fro, substantially as set forth.

14. The combination of the bolts, the lever Q, the lever I, pivoted thereto, the arbor, means, substantially as described, for intermittently engaging the arbor with the lever I, and means, substantially as described, for throwing the lever out of engagement with the 125 arbor when the door is shut, as set forth.

15. The combination of the arbor, the bolts, the lever Q, means, substantially as set forth, for detachably connecting said lever with the

bolts, and means, substantially as set forth, for intermittently engaging said lever with the arbor, as described.

16. The combination of the bolts, the lever Q, arranged to swing in planes transverse to the arbor, means, substantially such as described, for detachably connecting the bolts to said lever, and means, substantially such as described, for intermittently connecting the lever with the arbor, as set forth.

17. The combination of the arbor, the bolts, a laterally-swinging lever, a bar or arm connected to said swinging lever, variable permutation devices interposed between said bar or arm and the arbor, and operated by the rotation of the latter, and means, substantially such as described, for detachably connecting the bolts with the laterally-swinging lever, and thereby connecting them directly with the arbor which moves the permutation devices, as described.

18. The combination of the laterally-swinging lever Q, the bolts, the draw-bar which op-

erates the bolts, the pin r, carried by the swinging lever and adapted to engage with said draw-bar, the arbor, and means, arranged and operating substantially as described, for intermittently connecting said swinging lever with the arbor, substantially as set forth.

19. The combination of the arbor, the bolts, means, constructed and arranged substantially as set forth, for detachably connecting the arbor with the bolts, a series of tumblers constructed to alternately hold said connecting means out of engagement with the arbor, and means for permitting the engagement thereof with the arbor, a cam which throws said connecting means out of engagement with the arbor, and devices for transmitting power from the arbor to said cam.

In testimony whereof I affix my signature in presence of two witnesses.

JAMES WHITE.
